UNITED STATES PATENT OFFICE.

JOHN DURAN, OF WALTERSBURG, PENNSYLVANIA.

BOTTLE-STOPPER.

1,060,237.

Specification of Letters Patent.

Patented Apr. 29, 1913.

Application filed August 19, 1912. Serial No. 715,836.

To all whom it may concern:

Be it known that I, JOHN DURAN, a subject of the Emperor of Austria-Hungary, residing at Waltersburg, in the county of 5 Fayette and State of Pennsylvania, have invented certain new and useful Improvements in Bottle-Stoppers, of which the following is a specification, reference being had therein to the accompanying drawing.

10 This invention relates to bottle stoppers and has for its object to provide a device of such class in a manner as hereinafter set forth with valvular means whereby the stopper can be conveniently opened or closed 15 when occasion so requires.

Further objects of the invention are to provide a bottle stopper which is simple in its construction and arrangement, strong, capable of being detachably secured to the 20 bottle, efficient and convenient in its use and comparatively inexpensive to manufacture.

With the foregoing and other objects in view the invention consists of a novel construction, combination and arrangement of 25 parts as hereinafter more specifically described and illustrated in the accompanying drawings wherein is shown an embodiment of the invention, but it is to be understood that changes, variations and modifications 30 can be resorted to which come within the scope of the claims hereunto appended.

In describing the invention in detail, reference is had to the accompanying drawings wherein like reference characters denote corresponding parts throughout the several 35 views.

Figure 1 is an elevation of a bottle stopper in accordance with this invention showing the adaptation thereof in connection with a 40 bottle neck, the latter being shown in section, Fig. 2 is a vertical sectional view of a bottle stopper in accordance with this invention, showing the adaptation thereof in connection with a bottle neck, the latter being 45 illustrated in section, Fig. 3 is a top plan view of the bottle stopper, Fig. 4 is a section on line IV—IV Fig. 2, Fig. 5 is a section on line V—V Fig. 2, and Fig. 6 is a section on line VI—VI Fig. 2.

50 Referring to the drawings in detail 1 denotes the body portion of a bottle provided with a neck 2 providing a throat 3, the upper end of the neck 2 has its periphery formed with an annular bead 4. The foregoing elements are of known construction.

A bottle stopper in accordance with this

invention includes a resilient retaining collar 5 preferably formed of rubber and which frictionally engages the wall of the throat 3 at the upper end thereof. Extending 60 through the collar 5 and frictionally engaging therewith is a hollow cylindrical sleeve 6 formed integral at its upper end with the lower face of a circular disk 7. The disk is provided with a centrally disposed opening 65 8, the wall of which forms a continuation of the inner face of the sleeve 6. The disk 7 is seated upon the top edge of the neck 2 and is provided with a pair of oppositely disposed arms 9 which are bent to extend 70 around the bead 4 and engage the periphery of the neck 2 as clearly shown in Figs. 1 and 2. The arms 9, are detachably connected to the neck 2 by a flexible member 10 which engages with the lower ends of the 75 arms 9 and has its ends twisted together as at 11 whereby the arms 9 are maintained in engagement with the neck 2. The sleeve 6 at its lower end is formed with a diametrically opposed pair of valved outlets 12 80 through which the contents of the bottle can be discharged when the valvular member, to be presently referred to, is shifted to open the outlets 12. The inner face of the sleeve 85 3 constitutes a valve seat and which is engaged by an elongated hollow tubular valvular member 13, the latter being of a length as to project above and depend below the sleeve 6.

The member 13 near its lower end is 90 formed with a pair of openings 14, adapted when the member 13 is shifted, to register with the outlets 12 whereby the contents of the bottle can enter the member 13 and be discharged from the outer end thereof. 95 Mounted upon the lower end of the member 13 is an annular gasket 15 which is maintained in engagement with the lower end of the sleeve 6 by a collar 16 and fixedly secured to the member 13. Extending into 100 the inner end of the member 13 is a wedge-shaped block 17 which not only closes the inner end of the member 13 but also flares the said inner end whereby the collar 16 and gasket 15 are maintained in position upon 105 the inner end of the member 13.

The reference character 18 denotes a disk provided with a rim 19, the latter being cut away to form a pair of shoulders 20, 21. The disk 18 centrally thereof is formed with 110 a circular opening 22, the wall of which forms a continuation of the inner face of

the member 13, the latter being formed integral with the lower face of the disk 18.

- Formed integral with the edge of the disk 7 is a vertically disposed stop arm 23 which 5 is of a length as to project above the disk 18. The arm 23 is positioned in the path of the shoulders 20, 21 whereby the shifting movement of the disk 18 can be limited in either direction. When the arm 23 is not 10 in engagement with the shoulder 20 the openings 14 register with the outlets 12 and when the arm 23 abuts against the shoulder 21 the outlets 12 are closed by the valvular member 13.
- 15 The bottle stopper is detachably connected to the bottle neck so that it can be readily removed and used in connection with any bottle if desired. The closing of the outlets 12 by the member 13 prevent any foreign 20 matter from entering the outlet. The diameter of the sleeve 6 with respect to the inner diameter of the collar 5 is such that when the sleeve is mounted in position it will compress the collar 6, under such conditions 25 the sleeve 6 will be secured from vertical movement due to the binding action of the collar 5 between the wall of the throat of the neck and the periphery of the sleeve 6.
- What I claim is:—
- 30 A bottle stopper comprising a resilient collar adapted to frictionally engage the

neck of a bottle, a sleeve frictionally engaging with said collar and depending therefrom, an apertured disk formed integral with the top of said sleeve and provided 35 with a pair of arms and adapted to engage under the bead of a bottle neck for securing the disk thereto, said sleeve of greater length than said collar and at its lower end provided with a pair of outlets, a hollow vertical 40 member extending through and of greater length than said sleeve and provided with a pair of openings adapted to register with said outlets, a vertical arm projecting upwardly from the edge of said disk, a gasket 45 mounted upon the lower end of said member and abutting against said sleeve, a plug extending in the lower end of said member for closing it and for further flaring said lower end to maintain the gasket in engagement with said sleeve, a disk carried by 50 said member and having its edge cut away to provide a pair of shoulders capable of being engaged by said arm for limiting the movement of the member in either direction.

In testimony whereof I affix my signature in the presence of two witnesses.

JOHN DURAN.
